UNITED STATES PATENT OFFICE.

JOHN NEIL, OF NEW YORK, N. Y., ASSIGNOR TO THE BIGELOW CARPET COMPANY, OF SAME PLACE.

DESIGN FOR CARPET.

SPECIFICATION forming part of Design No. 12,162, dated February 8, 1881.

Application filed December 20, 1880. Term of patent 3½ years.

To all whom it may concern:

Be it known that I, JOHN NEIL, of New York, in the county and State of New York, have invented a new and original Design for Carpets, of which the following is a specification.

This invention relates to a new and original design for carpets and similar fabrics; and it consists in the novel grouping and configuration of figures hereinafter more fully described.

The accompanying photograph illustrates a face view of a carpet having my new design.

The group A is the central group of the design, and has running through and occupying its center a figure, *a*, which consists of feather-like figures resembling peacock-feathers branching out from a base of curving leaves. Surrounding this central figure, and defining the group, is a border, one portion of which consists of the curving leafy branch *b*, the other portions consisting of patterned stripes.

The group B, of which one portion appears at the top and another at the bottom of the photograph, contains a curving branch-like figure, *b*, with leaf-like projections upon it. This figure *b* is a continuation of and part of the branch *b*, bordering the figure A. The group B also contains another branch-like figure, *d*, somewhat similar to *b*, and which projects into the group B from the group D, and is a continuation of and part of the branch *d* of the group D. These two branches *d* and *b* occupy the center of the group B, whose outline is marked by a stripe inclosing the figures *d* and *b*.

The group C contains a peacock's feather, similar to that shown in the figure *a*, and also a curving leafy branch, *h*, which projects into the group. One portion of this group C is found toward the top of the photograph, and another at the bottom, and its outline is marked by a portion of the branch *b* and by a patterned border.

The group D contains a portion of the leafy

branch *d*, which projects out from it and into the group B, as already described, and is bordered by a patterned stripe. The group E consists of the rectangular figures *e f g*, having upon them different ornamental patterns.

I claim—

1. The design for carpets, consisting of the group A, containing the figures *a* and *b*, substantially as shown. 50
2. The design for carpets, consisting of the figure *a*, substantially as shown. 55
3. The design for carpets, consisting of the group B, containing figures *b* and *d*, substantially as shown. 55
4. The design for carpets, consisting of the group C, substantially as shown. 60
5. The design for carpets, consisting of the group D, containing figure *d*, substantially as shown. 60
6. The design for carpets, consisting of the group E, containing figures *e f g*, substantially as shown. 65
7. The design for carpets, consisting of the groups A, B, and C, substantially as shown. 65
8. The design for carpets, consisting of the groups B and D, substantially as shown. 70
9. The design for carpets, consisting of the figure *b*, substantially as shown. 70
10. The design for carpets, consisting of the figure *d*, substantially as shown. 75
11. The design for carpets, consisting of the figures *e* and *f*, substantially as shown. 75
12. The design for carpets, consisting of the figure *e*, substantially as shown. 80
13. The design for carpets, consisting of the figure *f*, substantially as shown. 80
14. The design for carpets, consisting of the groups A B C D E, containing figures *a b d e f g h*, substantially as shown.

JOHN NEIL.
